SINTERING MACHINE AND PALLET

Edward W. Shallock and William J. Urban,
Chicago, Ill., assignors to American Ore
Reclamation Company, Chicago, Ill., a corpo-
ration of New York

Application July 5, 1940, Serial No. 343,998

11 Claims. (Cl. 266—21)

The present invention relates to an improvement in sintering machines and pallets therefor.

Sintering machines of the Dwight & Lloyd type, now well known in the art and to which our invention is applicable, comprise a continuous track having a substantially horizontal upper run and a lower run which are connected at their ends by substantially semi-circular return bends. The pallets are propelled along the upper run of the track in endwise contact, where they are charged with the material to be sintered, and the material is ignited and sintered by down draft combustion in the continued travel of the pallets toward the discharge end, where the sinter is discharged; in a known manner. The pallets then pass down around the return bend at the discharge or delivery end of the machine and along the lower run of the track to the return bend at the feed end, where they are elevated to the upper run along which they are propelled, by known means.

In sintering machines of the continuous type referred to, the pallets at the return bends usually are held with the hub portions of each pallet in contact with the hub portions of the next adjacent pallets. The term hub portions as herein used denotes the bosses formed at the ends of the pallet frame for mounting the wheels. Each boss is formed so that its outer end surface is concentric with the axis of rotation of the associated wheel so that when two adjacent pallets pass around a curve the hub portions at the adjacent ends thereof are in contact. Since the individual pallets are frequently quite heavy, weighing from one thousand to twelve hundred pounds, the pressure exerted upon the hub portions of the pallets at the return bends is considerable, as will be appreciated.

When the pallets pass from a return bend to a straight section of the track, or vice versa, the hub portions thereof move in opposite directions and rub together under considerable pressure. This constant rubbing, and the frequently highly abrasive character of the materials handled, causes rapid wear of the end portions of the pallet frames, which necessitates frequent repair thereof to assure efficient operation of the machine. Instances are known in which the ends of the pallet frames, due to neglect, have become so badly worn that the wheels of adjacent pallets touch each other and the end plates of the pallets diverge defining openings between them, causing objectionable air leakage between pallets passing along the upper run of the track.

It is an object of the present invention to pro-

vide means whereby the hub portions of adjacent pallets roll upon each other without objectionable rubbing upon entering or leaving straight sections of the track, thereby substantially eliminating wear of the end portions of the pallet frames. We provide guide means at each of the points of transition from straight track to curve track or curve track to straight track, each pallet having means cooperating with the guide means to attain rolling of the hub portions upon each other as stated. More specifically, we provide guide sections at each of the transition portions of the track, and a train of pallets having front and rear guide wheels which travel upon the track and cooperate with the guide sections and cams with which the latter are provided in such manner that the contacting hubs of adjacent pallets in effect roll one on the other without objectionable relative movement and rubbing together thereof, when the wheels of the pallets are passing along any transition portion of the track. Other objects and advantages will appear from the following detail description.

25 In the drawings:

Figure 1 is a side view of a sintering machine and pallets therefor constructed in accordance with the principles of our invention;

Figure 2 is an enlarged side elevation of a portion of the return bend and upper run at the feed end of the sintering machine and pallets of Figure 1;

Figure 3 is a fragmentary sectional view taken substantially on line 3—3 of Figure 2, certain parts being shown in elevation;

Figure 4 is a fragmentary sectional view taken substantially on line 4—4 of Figure 2, certain parts being shown in elevation;

Figure 5 is an enlarged side elevation of a portion of the upper run and return bend at the discharge end of the sintering machine of Figure 1;

Figure 6 is a fragmentary sectional view taken substantially on line 6—6 of Figure 5, certain parts being shown in elevation;

Figure 7 is a fragmentary sectional view taken substantially on line 7—7 of Figure 5, certain parts being shown in elevation;

Figure 8 is an enlarged side elevation of a portion of the return bend and lower run at the discharge end of the sintering machine of Figure 1;

Figure 9 is a fragmentary sectional view taken substantially on line 9—9 of Figure 8, certain parts being shown in elevation;

Figure 10 is a fragmentary sectional view taken substantially on line 10—10 of Figure 8, certain parts being shown in elevation;

Figure 11 is an enlarged side elevation of a portion of the lower run and return bend at the feed end of the sintering machine of Figure 1;

Figure 12 is a fragmentary sectional view taken substantially on line 12—12 of Figure 11, certain parts being shown in elevation; and

Figure 13 is a fragmentary sectional view taken substantially on line 13—13 of Figure 11, certain parts being shown in elevation.

Referring now to Figure 1, our sintering machine, in general, is of known construction and includes a suitable main supporting frame 6. An endless track 7 is suitably mounted upon the frame and comprises upper and lower horizontal runs 8 and 9, respectively, connected by return bends 10 and 11 at the feed end and discharge end, respectively, of the machine.

According to our invention we incorporate in such an endless track, guide track sections 12, 13, 14 and 15 at the portions of transition from curved to straight track or straight to curved track, i. e., at the return bend 10 and upper run 8 at the feed end, upper run 8 and return bend 11 at the delivery end, return bend 11 and lower run 9 at the delivery end, and lower run 9 and return bend 10 at the feed end, respectively, of the sintering machine. These several guide sections provide means which, together with a special construction of the pallets, functions to achieve the objects of the invention and which will be described in detail hereinafter.

A train of separate pallets 16 are adapted to be propelled along the track in the direction indicated by the arrows in Figure 1, by any suitable means which may be driven from a drive shaft 17 which is suitably mounted for rotation upon the supporting frame 6. One suitable mechanism for this purpose is disclosed in United States Patent No. 1,764,695, dated June 17, 1930. Obviously any other suitable or preferred means for driving the machine may be employed.

A feed hopper 19 and igniter 20 are disposed above the upper run 8, adjacent the feed end of the machine, and a plurality of windboxes 21 are disposed below and closely adjacent the upper run 8, in a manner well known in the art for the purposes previously set forth.

Referring now to Figures 2 through 4, the guide section 12 is suitably fixed between return bend 10 and upper run 8 of the track at the feed end of the machine. Guide section 12 comprises a plate member 25 which is provided with opposed upper and lower flanges 26 and 27, respectively, which are directed inwardly of the sintering machine, the upper face of the flange 27 being formed with a cam surface 28 extending substantially the entire length of the guide section. A groove 29, at the inner edge of flange 27, extends for a major portion of the length of the flange.

Each pallet 16 comprises a substantially rectangular frame 30, disposed transversely of the frame of the machine, provided at each side with downwardly extending integral hubs 31. The latter receives stub shafts 32 upon which flanged front wheels 33 and flanged rear wheels 34 are journaled. Side plates 35 are secured to each of the pallet frames. The outer surfaces of the hub portions 31 are concentric with the respective stub shafts 32 and the ends of the side plates 35 are tangent to the hub portions so that the ends of the side plates of adjacent pallets abut each

other when traveling along the upper run, as shown in Figure 1. The front wheels 33 of the pallets are each provided with an inner tread portion 37 and outer tread portions 38 and 39, the tread portion 37 preferably being of slightly larger diameter than the tread portions 38 and 39, which are of equal diameter. The tread portions 38 and 39 are simply separate areas of a single outwardly extending cylindrical portion of the wheel 33, as indicated by the dot-dash line in the several figures. Each of the rear wheels 34 comprises tread surfaces 40 and 41 of equal diameter which are also simply separate areas of the wheel. The diameter of the rear wheel treads 40 and 41 is the same as that of the tread portion 37 of the front wheel 33.

The pallets in passing from return bend 10 enter guide section 12, whereupon the tread surface 37 of the front wheel will ride upon the surface 20 at the bottom of groove 29 and the tread portion 41 of the rear wheel will ride upon the cam surface 28.

Referring to Figure 2, it will be noted that groove 29 diminishes in depth from its central portion toward each end. We have shown three pallets disposed with their hub portions in contact, of which the first is passing from guide section 12 onto the straight upper run of the track, the second is passing through the guide section, and the third is passing from the return bend 10 into the guide section 12. As the first pallet approaches upper run 8 of the track, tread portion 37 of its front wheel travels upward along the inner portion of the lower wall of groove 29, causing tilting or swinging of this pallet in a counter-clockwise direction about the axis of its rear wheels. At the inner end of groove 29 tread portion 37 of the front wheel enters upon the rail of upper run 8 of the track, and at the same time, tread portion 41 of the rear wheel enters upon the upper horizontal portion of cam element 28, this latter portion of the cam element being in the plane of the upper surface of the upper run of the corresponding track rail. Thereafter no further tilting of the first pallet occurs during its travel along the upper run of the track.

During the first portion of the referred to travel of the first pallet, the tread portion 37 of the front wheel of the second pallet travels upon the lower wall of groove 29 at the deeper portion thereof, and tread portion 41 of the rear wheel of the second pallet is entering upon the cam element 28 and subsequently travels upward along the high portion of cam element 28. That causes tilting of the second pallet in a clockwise direction about the axis of its front wheels, at the same rate as the tilting of the first pallet, cam element 28 and the lower wall of groove 29 being appropriately formed to that end. Accordingly, the abutting hub portions 31 of the first and second pallets merely roll one on the other in opposite directions and at the same rate, with no objectionable rubbing therebetween, during the referred to portion of the travel of the first and second pallets. During the second portion of the travel of the first and second pallets, after tread portion 41 of the rear wheel of the first pallet enters upon the horizontal portion of cam element 28, hub portion 31 of the second pallet continues to roll in a clockwise direction, in contact with hub portion 31 of the first pallet, until the ends of the side plates of the second pallet are brought into contact with the ends of the side plates of the first pallet. At that time tread portion 41 of the rear wheel of the second pallet passes onto the horizontal por-

tion of cam element 28, and the first and second pallets then travel onto and along the upper run of the track in endwise abutting relation one to the other.

With the pallets moving from the positions shown in Figure 2 toward the upper run of the track, tread portion 37 of the front wheel of the third pallet travels upward along the bottom wall of groove 29. This causes tilting of the third pallet in counter-clockwise direction about the axis of its rear wheels, and the abutting hub portions 31 of the second and third pallets roll one upon the other in opposite directions, without objectionable rubbing therebetween. In the continued travel of the pallets, tread portion 37 of the front wheel of the third pallet enters the deeper portion of groove 29 and this pallet is then tilted clockwise about the axis of its rear wheels, as the tread portion 37 of the front wheel of the second pallet travels up the inclined inner portion of the lower wall of groove 29, causing tilting of the second pallet in counter-clockwise direction about the axis of its rear wheels. Accordingly, the abutting hub portions 31 of the second and third pallets roll one on the other in opposite directions and at the same rate, the movements between the second and third pallets, from that point on, being the same as the movements between the first and the second pallets previously described.

It will be seen that the abutting hub portions of pallets passing from the return bend 10 to the upper run 8 of the track have rolling contact one on the other, without objectionable rubbing therebetween. The abutting hub portions of adjacent pallets roll in opposite directions, but the movement of adjacent end portions of the pallets, either inward or outward, is in the same direction. The above explanation of the mode of operation of our invention will perhaps be better understood if it is compared to the action which is found in the ordinary link chain. When such a chain passes around a sprocket, adjacent links, which are pivoted on a common axis, rotate a limited extent about this axis. Now it will be seen that if lines are drawn through the two pivots of the links, respectively, the points of intersection of such lines of adjacent links passing about the sprocket will always lie upon the arc of a true circle. We have applied that same principle to our sintering machine. Referring to Figure 1, it will be seen that the return bend 10 is concentric with the axis of rotation of drive shaft 17 and return bend 11 is also concentric with a definite center point. When the pallets pass through these portions of the track, the points of intersection of lines drawn through the front and rear wheels of the pallets, respectively, will be upon an arc concentric with the centers of the return bends 10 and 11. However, in sintering machines in which the return portions of the track are semi-circular the intersection of the lines passing through the wheel centers of the respective pallets, will not lie upon an arc concentric with the center of the bend when the pallets leave or enter the straight portions of the track. We have, therefore, provided the guide track sections 12, 13, 14 and 15 at each of these transition portions of the track. These guide track sections and the front and rear wheels of the pallets are so constructed and arranged that the intersection of the lines extending through the front and rear wheels of the pallets, respectively, will lie, or substantially lie, upon an arc concentric with the center of the return bends 10 and 11. For convenience of description, we have referred to but one front and

one rear wheel of the respective pallets. It will be understood, of course, that each pallet has two front and two rear wheels, and that the spacing between the axes of the front and rear wheels is the same on all of the pallets, the radius of the arc of swinging or tilting of the pallets thus being the same in each instance. Likewise, two guide sections 12, 13, 14, and 15 are provided one at each side of the sintering machine for guiding a front and a rear wheel at each side of the pallets. The lower wall of each groove 29 and each cam element 28 are, of course, appropriately formed to impart to the pallets the desired tilting movements as above described.

The guide section 13 may be formed with a substantially straight portion 45 such as disclosed in the previously mentioned Patent No. 1,764,695. This section comprises lower and upper inwardly extending flanges 47 and 49, respectively, the inner face of the flange 47 has a cam surface 46 at the outer edge thereof and, at its inner edge, is provided with a groove 48 extending substantially along the entire length of the guide section. At this portion of transition of the track the tread portions 39 of the front wheels of the pallets will ride upon the cam surface 46 and the tread portions 40 and 41 of the rear wheels of the pallets will engage the upper inner surface of the groove 48. Referring to Figure 5, it will be seen that we have shown a pair of pallets, the forward one of which has its front wheels in the arcuate return bend 11 and its rear wheels disposed in the guide section 13. The following pallet is completely within the guide section and the tread portion 39 of its forward wheel is riding up the cam surface 46 tending to tilt the pallet about the axis of its rear wheel in a counter-clockwise direction, together with the forward pallet which is tilting in a clockwise direction about the horizontal axis of its forward wheel, which causes the abutting hubs 31 to roll upon each other at the same rate. After the pallets pass through the guide section 13 to circular bend 11, the forward wheels travel on their treads 37 and the rear wheels on their treads 40.

The pallets after passing around the circular bend 11 will enter guide section 14 at the next transition portion of the endless track in their travel therearound, and reference may be had to Figures 8 through 10 for a showing thereof. The guide section 14 consists of a plate member 50 having inwardly directed upper and lower flanges 51 and 52, respectively, flange 52 being provided at its inner surface and along the outer edge with a suitably formed cam surface 54. The flange 52 is provided with a groove 55 along the inner edge extending substantially the entire length of section 14. The tread surface 39 of the front wheels of the pallets ride along the cam surface 54 and the tread surfaces 41 and 40 of the rear wheels ride upon the surface of the groove 55. Reference may be had to Figure 8 in which we have shown three pallets, the first of which is entering the lower run 9, the second in passing through the guide section, and the third is entering the guide section. The forward pallet is tilting about the axis of its front wheels in a counter-clockwise direction and the second pallet is tilting in a clockwise direction about the axis of its rear wheels, since its rear wheels are entering the deeper portion of groove 55. It will be apparent that the abutting hubs of the first and second pallets will roll upon each other. The forward wheels of the third pallet, which is entering the guide section, are riding up upon the in-

clined portions of cam 54 tilting the pallet in a counter-clockwise direction about the axis of its rear wheels and it will be apparent that the abutting hubs 31 of the second and third pallets will roll upon each other at the same rate. The pallets after entering lower run 9 will again ride upon treads 37 of the front wheels and treads 40 of the rear wheels.

In Figures 11 through 13, the guide section 15 is fixed between the lower substantially horizontal run 9, and return bend 10 at the feed end of the machine and comprises a plate member 60 having inwardly directed upper and lower flanges 61 and 62 respectively. A cam surface 63 is formed along the outer edge of the inner surface of lower flange and has a groove 64 extending substantially along the entire length of the guide section 15. The pallets in passing along this transition portion ride upon the tread portion 37 of the front wheels upon the inner surface of the groove 64, and the treads 41 of the rear wheels ride upon cam surfaces 63. In Figure 12 we have shown three pallets, the first of which is entering the return bend 10, the second pallet is passing through the guide section, and the third pallet is entering the guide section. The first pallet will tilt in a counter-clockwise direction about the axis of its front wheels, the second pallet will tilt in a clockwise direction about the axis of its rear wheels, since tread area 37 of the front wheel is riding up the inclined surface at the bottom of groove 64, and the third pallet will tilt in a counter-clockwise direction. Thus the abutting hubs 31 of adjacent pallets will roll upon each other at the same rate, the cam surface being appropriately designed to that end. The pallets when fully in the arcuate return bend 10 will ride upon tread portions 37 of the front wheels and treads 40 of the rear wheels.

So far as we are aware in the constructions known in the art the abutting hub portions of adjacent pallets are not symmetrically related and will slide upon each other in passing around curved sections of track, while with our invention the symmetrical relation of the hubs is always maintained.

The embodiment shown and described is the preferred form of our invention, but it will be understood that various modifications may be made without departing from the spirit and scope of the appended claims.

We claim:

1. In a sintering machine, a continuous track comprising upper and lower straight sections connected at their ends by return bends, a train of pallets adapted to travel upon said track in abutting relation, said pallets having hub portions at their ends adapted to permit adjacent pallets to roll upon each other in passing through said return bends, and means for preventing relative sliding movement of said abutting hub portions of adjacent pallets upon each other when the latter are passing to and from said straight sections of said track.

2. In a sintering machine, a continuous track comprising upper and lower straight sections of track and substantially semi-circular return bends, guide means connecting said straight sections to said return bends, and a train of separate pallets traveling upon said track in abutting relation, said pallets having hub portions at their ends adapted to permit adjacent pallets to roll upon each other in passing through said guide means and said return bends, said guide means and said pallets having cooperating means for

preventing relative sliding movement of said hub portions of adjacent pallets upon each other when the latter are passing through said guide means.

3. In a sintering machine, a continuous track comprising upper and lower straight sections of track and substantially semi-circular return bends, guide sections connecting said straight sections to said return bends, and a train of separate pallets each having front and rear guide wheels travelling upon said track, said pallets having hub portions at their ends adapted to permit adjacent pallets to roll upon each other in passing through said guide sections and said return bends, said wheels cooperating with said guide sections for preventing relative sliding movement of said hub portions of adjacent pallets upon each other when the latter are passing through said guide sections.

4. In a sintering machine, a track, a train of pallets each having front and rear wheels travelling on said track, means for guiding said pallets, said pallets having hub portions at their ends adapted to permit adjacent pallets to roll upon each other in passing through said guiding means, said guiding means comprising upper and lower flanges, a cam extending along the inner surface of said lower flange adjacent one edge thereof, a groove adjacent the other edge of said lower flange, said front and rear wheels of each of said pallets being adapted to travel between said flanges, each of said front wheels having a tread area adapted to ride in said groove, and each of said rear wheels having a tread area adapted to ride upon said cam, said cam and said groove being shaped to coat with said front and rear wheels of said pallets to tilt said pallets to prevent relative sliding movement of said hub portions of adjacent pallets upon each other in passing through said guiding means.

5. In a sintering machine, a track, a train of pallets each having front and rear wheels travelling on said track, means for guiding said pallets, said pallets having hub portions at their ends adapted to permit adjacent pallets to roll upon each other in passing through said guiding means, said guiding means comprising upper and lower flanges, a cam extending along the inner surface of said lower flange adjacent one edge thereof, a groove adjacent the other edge of said lower flange, said front and rear wheels of said pallets being adapted to travel between said flanges, each of said front wheels having a tread area adapted to ride upon said cam, each of said rear wheels having a tread area adapted to ride in said groove, said cam and said groove being adapted to coat with said front and rear wheels of said pallets to tilt said pallets to prevent relative sliding movement of said hub portions of adjacent pallets upon each other in passing through said guiding means.

6. In a sintering machine, a track, a train of pallets each having front and rear wheels travelling on said track, a member for guiding said pallets, said pallets having hub portions at their ends adapted to permit adjacent pallets to roll upon each other in passing through said guide member, said guide member comprising a cam extending adjacent one edge thereof and having a groove adjacent its other edge, said cam and said groove of said guide member being shaped to coat with each of said front and rear wheels of said pallets to tilt said pallets to prevent relative sliding movement of said hub portions of adjacent pallets upon each other in passing through said guide member.

7. In a sintering machine, a track, a train of pallets each having front and rear wheels travelling on said track, means for guiding said pallets, said pallets having hub portions at their ends adapted to permit adjacent pallets to roll upon each other in passing through said guiding means, said guiding means comprising a member having opposed upper and lower flanges, a cam extending along the upper surface of said lower flange adjacent one edge thereof, said latter flange having a groove adjacent its other edge, said front and rear wheels of said pallets being adapted to travel between said flanges, each of said front wheels having three tread areas of which the outer and intermediate treads are of equal diameter and the inner tread of larger diameter than said outer and intermediate treads, each of said rear wheels having inner and outer tread areas equal to the diameter of said inner tread of each of said front wheels, said inner tread of each of said front wheels being adapted to ride in said groove and said outer tread of each of said rear wheels being adapted to ride upon said cam, said cam and said groove being shaped to coact with said front and rear wheels of said pallets to tilt said pallets to prevent relative sliding movement of said hub portions of adjacent pallets upon each other in passing through said guiding means.

8. In a sintering machine, a track, a train of pallets each having front and rear wheels travelling on said track, means for guiding said pallets, said pallets having hub portions at their ends adapted to permit adjacent pallets to roll upon each other in passing through said guiding means, said guiding means comprising a member having opposed upper and lower flanges, a cam extending along the upper surface of said lower flange adjacent one edge thereof, said latter flange having a groove adjacent its other edge, said front and rear wheels of said pallets being adapted to travel between said flanges, each of said front wheels having three tread areas of which the outer and intermediate treads are of equal diameter and the inner tread of larger diameter than said outer and intermediate treads, each of said rear wheels having inner and outer tread areas equal to the diameter of said inner

tread of each of said front wheels, said outer tread of each of said front wheels being adapted to ride upon said cam, and said inner and outer treads of each of said rear wheels being adapted to ride in said groove, said cam and said groove being shaped to coact with said front and rear wheels of said pallets to tilt said pallets to prevent relative sliding movement of said hub portions of adjacent pallets upon each other in passing through said guiding means.

9. A pallet comprising, a frame having a pair of front wheels and a pair of rear wheels, said front wheels each having three tread areas two of which are of equal diameter and the third tread of greater diameter, said rear wheels each having two tread areas of a diameter equal to the diameter of said third tread of said front wheels.

10. A pallet comprising, a frame having a pair of front wheels and a pair of rear wheels, said front wheels each having three tread areas two of which are of equal diameter and the third tread of greater diameter, said rear wheels each having two tread areas of a diameter equal to the diameter of said third tread of said front wheels, said frame having a plurality of hub portions one for each of said wheels for mounting said wheels thereon, the outer surface of each of said hub portions being concentric with its respective pallet wheel.

11. In a sintering machine comprising, an endless track, and a train of pallets having wheels riding upon said track, said pallets having hub portions at their ends adapted to permit adjacent pallets to roll upon each other in passing through curved portions of said track, a guide means comprising a member having opposed upper and lower flanges, a cam extending along the upper surface of said lower flange adjacent one edge thereof, and a groove in said lower flange adjacent the other edge thereof, said cam and said groove being shaped to coact with said wheels to tilt said pallets to prevent relative sliding movement of said hubs of adjacent pallets upon each other in passing through said guide means.
